UNITED STATES PATENT OFFICE.

ARTHUR D. SABORSKY, OF CLEVELAND, OHIO, ASSIGNOR TO THE ADVANCE MANUFACTURING COMPANY, OF DETROIT, MICHIGAN, A CORPORATION OF MAINE.

STORING MECHANISM FOR TYPE.

Original application filed January 6, 1917, Serial No. 140,989. Divided and this application filed July 12, 1920. Serial No. 395,736.

To all whom it may concern:

Be it known that I, ARTHUR D. SABORSKY, a citizen of the United States, residing at Cleveland, in the county of Cuyahoga and State of Ohio, have invented certain new and useful Improvements in and Relating to Storing Mechanism for Type, of which the following is a specification.

This invention relates to mechanism for holding and storing type.

One object of the invention is to provide an improved type storing or holding mechanism which permits the easy and rapid distribution of type thereto and setting of the type therefrom.

Another object of the invention is to provide an improved storing mechanism for perforated type having a plurality of members, one for each character of type, around which the perforated type are stacked and means which support the members, but permit the distribution of type to them at one end and movement of the type from end to end thereof.

Another object of the invention is to provide a plurality of storing devices for type and improved means for supporting said devices, whereby the distributing and positioning of the type for setting is facilitated.

Other objects of the invention will be apparent to those skilled in the art to which my invention relates from the following description taken in connection with the accompanying drawings.

For the purpose of illustration, I have, in the accompanying drawings, shown and herein described one form of mechanism embodying my invention.

Fig. 1 is an elevation of a storing mechanism embodying my invention.

Fig. 2 is a top plan view, partly broken away.

Fig. 3 is a side elevation.

Fig. 4 is a fragmentary sectional view with the type distributing device in position ready to distribute a type section.

Figs. 5 and 6 are views similar to Fig. 4, but showing somewhat in detail the position of the elements when the type is allowed to drop to its storing position.

Fig. 7 is a sectional view on the line 7—7 of Fig. 4.

Fig. 8 is a sectional view on the line 8—8 of Fig. 4.

Fig. 9 is a fragmentary sectional view on the line 9—9 of Fig. 1.

Fig. 10 is a fragmentary sectional view on the line 10—10 of Fig. 9.

Figs. 11 and 11^a are respectively side and plan views of a type section.

Fig. 12 is a detail view showing the manner of setting type.

Fig. 13 is a detail view of the devices which control the operation of the supporting means for the storing bars.

Fig. 14 is a fragmentary view showing a slightly modified form of the invention.

In the drawings, 1 indicates a frame or support preferably comprising a pair of side members A, A, and a platform B connected at its opposite ends in any desired manner to the side members A, A. The upper and lower ends of the side members A are preferably bent outwardly at right angles, as shown at a, a', the bent ends a' serving as supports to which the opposite ends of the platform B may be secured and the bent ends a serving as feet on which the frame 1 rests.

C indicates a supporting member extending between the side members A in a plane below the platform B, and adapted to support the type T in stacked relationship, in the manner hereinafter set forth. The type T are each perforated or formed with an opening through its body, as shown in Figs. 11 and 11^a. By reason of the fact that I have heretofore used perforated type on a rotatable printing drum, I have merely for illustrative purposes shown type having tapering sides.

D indicates a series of bars or rods, one for each letter, number and other character of the front of type used, preferably arranged side by side, (but spaced from each other a suitable distance), and co-operating with the supporting member C to hold or store the type as shown in Figs. 1 and 14. The bar C is preferably provided with a rear wall e, which may be formed integrally with the supporting member C.

12 indicates a plate extending along and adjacent to the front edge of the bar or member C and provided with a series of partitions 12', which extend inwardly, their free ends preferably engaging the rear wall e. The plate 12 may be secured in position in any well known manner. As shown in Fig.

9, the plate 12, the inwardly extending members or partitions 12' and the rear wall *c*, co-operate to form pockets 12^a for the lower ends of the stacks of type, but prevent them 5 from moving laterally, except as hereinafter described. The plate 12 is provided with a series of openings or cut-away portions 13, one for each pocket 12^a, through which the lowermost type of each type stack may be 10 moved in setting the type, as will be later described. Below and centrally of each pocket, the wall of the supporting member *C* is cut away or recessed, as shown at 14 in Figs. 1, 9, 10 and 12, so as to permit the 15 insertion or positioning of a type setting device, indicated by 15. The type setting device may be a suitable tool, but preferably it consists of a type holding segment, such as is used for holding the type *T* to 20 the drum of a printing machine. When the holding device 15 is used, the type is set ready for positioning on the printing drum. The opposite side walls of each recess 14 25 preferably diverge so as to permit the ready insertion of the device 15 (see Fig. 12).

Each of the rods *D* is vertically supported intermediate its ends by means, indicated as an entirety by 16, with its lower free end slightly above the bottom, but substantially centrally, of the adjacent pocket 12^a. The lower free end of each rod *D* is spaced from the bottom of the adjacent pocket a distance more than the thickness of a single type but less than the thickness of 35 two type. By this arrangement the lowermost type may be moved laterally through the adjacent slot 13, but the next section of type above will be held against movement by the rod *D* until the lowermost type has 40 been removed and it then moves downwardly onto the bottom of the pocket. It will thus be seen that only one section of type, the lowermost section in each stack, can be removed at a time. The rods *D* are preferably of varying lengths so that their lower free ends may terminate at suitable distances from the supporting member *C* according to the thickness of the type which each rod holds; likewise the slots 13 preferably vary in length to co-operate with the 45 respective rods adjacent thereto. The lower free end of each rod *D* is held substantially stationary or against swinging movement by engagement with the walls of the type *T* which substantially fill the adjacent pocket 12^a.

The type holding bar or tool 15 is moved from below upwardly into engagement with the walls of the opening in the lowermost 60 type and then moved forwardly; this operation will cause the lowermost type of the stack to slide out of the adjacent pocket through the opening 13 and simultaneously ring itself on the bar 15, as shown in Fig. 12.

65 The supporting means 16 for each rod *D*

preferably comprise two pairs of members 16^a, 16^a, and 16^b, 16^b, which pairs are spaced from each other so as to engage and support the adjacent rod at two different points intermediate its ends. By this arrangement the upper end of the rod is free and exposed in position to permit type to be ringed or threaded thereon. The engaging members of each pair are slidably supported, whereby they can be simultaneously moved toward and from the adjacent rod. 70 16^a, 16^a, indicate pairs of plates extending between and preferably connected at their opposite ends, in any well known manner, to the side members *A*. One pair of plates 16^a, 16^a, is in front of and common to the rods *D*, and the other pair of plates 16^b, 16^b, is in rear of and common to the rods *D*. The plates 16^a, 16^a, of each pair are arranged parallel to each other and formed with series of upper and lower aligned openings 16² to slidably receive the upper and lower rod engaging members 16^a, 16^b, on the adjacent side of the rods *D*. The inner ends of the rod supporting members 16^a, 16^b, are preferably cut away or recessed 75 to receive the opposite edges of the rods *D*, (see Fig. 8), while the latter are formed with notches 16^c, at their opposite sides to receive the inner ends of the supporting members 16^a, 16^b, and also to form shoulders 80 which rest thereupon.

Each pair of supporting members 16^a or 16^b supports, independently of the other pair of members, the adjacent rod *D*, so that either pair of members may be moved laterally away from the rod *D*, as will be later described.

17 indicates as an entirety means for controlling and operating the pairs of engaging members 16^a, 16^b. The operating means 17 preferably control and actuate both series of pairs of members alternately, and in operation serve to maintain one series of pairs of members in engagement with the rods *D* while moving the other series of pairs of members away from and toward them. The operating means 17 is preferably operated by a lever 17', or equivalent element. Upon each operation of the lever 17', both series of pairs of engaging and supporting members 16^a, 16^b, are alternately operated to disengage and engage the rods *D*. The operating means serves to so control one series of pairs of engaging members while the other series is moving away from and toward the rods, that the latter will be supported at all times, as shown in Figs. 5 and 6, with their lower free ends slightly above the pockets 12^a, as already 110 described.

By this construction and arrangement the types or type sections *T* may be ringed on the free ends of the rods *D* and they will then drop by gravity onto the upper pairs 115 120 125 130

of engaging members 16^a, but upon the movement thereof laterally the types or type sections T on the rods D will fall or drop by gravity downwardly into engagement with the engaging members 16^b, where they will rest until the latter are moved laterally; thereupon the types of type sections T will fall by gravity downwardly until they are arrested by the types already ringed or stacked on the rods D. By operating the upper and lower pairs of engaging members alternately, and so controlling their operation that one series of said pairs will engage and support the rods at all times, the types will automatically slide endwise of the rods without causing the rods to be removed, displaced or dismantled.

Of the operating means, 17^a, 17^b, indicate a pair of rock-shafts loosely mounted at their opposite ends in suitable bearings in the side members A, A, upon opposite sides of the rods D. 17^b, 17^{b'}, indicate pairs of arms, one pair for the adjacent upper and lower rod engaging members 16^a, 16^b, at either side of each rod D. The arms 17^b, 17^{b'}, are fixed to the rock shafts 17^a and extend in opposite directions therefrom. The arms 17^b, 17^{b'}, of each pair are preferably formed integral and provided at their central portions with a hub through which the adjacent shaft 17^a extends. Each hub is secured to the adjacent shaft 17^a in any well known manner. Each of the shafts 17^a is preferably arranged between the adjacent pair of supporting plates 16', 16', and substantially midway between the upper and lower adjacent rod engaging members 16^a, 16^b, so that the arms 17^b, 17^{b'} will be substantially equal in length and impart the same amount of movement to the upper and lower engaging members. 17^c indicates a projection provided on each of the rods 16^a, 16^b, and adapted to be engaged by the adjacent arm 17^b or 17^{b'}, carried by the adjacent rock shaft 17^a, to move the adjacent rod engaging member laterally away from the adjacent rod D. 17^d indicates a coiled spring preferably surrounding each of the rods 16^a, 16^b, and interposed between the adjacent arm 17^b or 17^{b'} and a stop 17^e provided on the rod 16^a or 16^b. The rods 16^a, 16^b, are preferably offset to provide shoulders which form the projections 17^c and stops 17^e. The shoulders formed by said offset on the opposite side of each rod 16^a, 16^b, preferably serve as stops to limit the inward and outward movements of the rod. 17^f indicates a collar or washer which may be interposed between each arm 17^b or 17^{b'} and the adjacent spring 17^d so as to form a suitable abutment for the spring and engaging device for the adjacent arm 17^b or 17^{b'}. The spring 17^d serves normally to maintain the rods inwardly against the adjacent rod D and at the same time permit movement of the adja-

cent arm 17^b or 17^{b'} inwardly or toward the rod D without transmitting motion to the adjacent rod engaging member 16^a or 16^b.

The normal position of the arms 17^b, 17^{b'}, is shown in Figs. 4 and 8. To operate the arms 17^b, 17^{b'}, the shafts 17^a, 17^a, are simultaneously rocked in opposite directions from normal position, first in one direction and then in the other direction, so that the arms 17^b, 17^{b'}, will be moved laterally to opposite sides of their normal position each time the shafts 17^a are operated. The shafts are first rocked to move the upwardly extending arms 17^b outwardly or away from the rods D and the downwardly extending arms 17^{b'} inwardly or toward the rods D. In so operating, the arm 17^b will engage the projections 17^c on the members 16^a and simultaneously move the latter laterally or away from the rods D, permitting any type which has been distributed upon the upper ends of the rods D to drop downwardly on to the engaging members 16^b; at the same time the arms 17^{b'} are moved inwardly against the tension of the springs 17^d. The shafts 17^a are then rocked in the opposite direction. The arms 17^b swing in the opposite direction, engaging the collars 17^f and acting through them and the springs 17^d to return the engaging members 16^a into engagement with the rods D; at the same time the arms 17^{b'} swing in the opposite direction, engaging the projection 17^c on the members 16^b and simultaneously move the latter laterally or away from the rods D, at which time the type which have dropped thereonto will be released and allowed to slide down the rods D. Finally the shafts 17^a are rocked back to normal position, the arms 17^{b'} acting through the adjacent collars 17^f and springs 17^d, to move the engaging members 16^b into engagement with the rods D as they return to their normal position.

It will be understood that all the arms 17^b, 17^{b'} are operated simultaneously first laterally to one side of their normal position and then laterally to the opposite side of their normal position, so that one series of pairs of members 16^a will be simultaneously moved out of and into engagement with the rods D and thereafter the other series of pairs of members 16^b will be simultaneously moved out of and into engagement with the rods D. This construction and operation permits the operator to distribute a considerable number of type sections, and then by a single operation of the lever 17^f to allow all of the type so distributed to drop or slide down the rods D to a position ready to be set.

18 indicates a pair of gear sectors rigidly connected to corresponding ends of the rock shafts 17^a and meshing with each other, whereby the shafts may be rocked simultaneously in opposite directions, the purpose

of which is to alternately control and actuate the series of pairs of rod engaging or supporting members, 16^a, 16^b, maintaining one series in engagement with the rods D and simultaneously moving the other series away from and toward the rods D, as above described. When stationary or in normal position, the sectors 18 mesh with each other substantially midway between their opposite ends, so that they can be rocked upwardly and downwardly relative to their normal position to completely operate the rock shafts 17^a.

19 indicates as entirely devices interposed between the lever 17' and one of the gear sectors 18 for rocking the latter upwardly, downwardly and back to normal position. Of these devices, 19^a indicates a shaft or pivot pin fixed in any well-known manner to one of the side members A and serving as a fulcrum for the lever 17'. 19^b indicates a rack or gear sector connected to and preferably formed integral with the lever 17' and meshing with a pinion 19^c. The pinion 19^c is preferably fixed to or formed integrally with a shaft 19^d which is mounted in any suitable manner in a bearing fixed to and extending laterally from the adjacent side member A. The pinion 19^c is rotated in one direction (anti-clockwise) when the outer end of the lever 17' is moved downward, and is then rotated in the opposite direction (clockwise) when the lever 17' returns to its first position. Preferably the rack on the sector 19^b is long enough to rotate the pinion slightly more than one revolution for a purpose to be later set forth. 20 indicates a link preferably pivotally connected on the outer end of the shaft 19^d and swingable thereabout. 20^a indicates a connecting member or rod pivotally connected at its lower end to the free end of the link 20 and pivotally connected at its upper end to an arm 20^b which is preferably integrally connected with one of the gear sectors 18. The link 20 is adapted to be swung or revolved around the axis of the shaft 19^d and in so doing, serves to swing the arm 20^b upwardly and then downwardly past its normal position and back to its starting position as the link 20 makes one complete revolution. For this purpose I preferably interpose between the link 20 and the pinion 19^c suitable connections, indicated at 21, constructed and arranged so as to be connected to the pinion 19^c when the latter is rotated in one direction and be disengaged or released therefrom when the pinion rotates in the opposite direction. The connections 21 are preferably arranged to revolve the link 20 as the pinion rotates in an anti-clockwise direction due to the downward movement of the lever 17'. Of these connections, 21^a indicates a projection or lug secured to and extending substantially

radially of the shaft 19^d. 21^b indicates a dog or pawl pivotally mounted on the inner side of the link with its nose disposed in the path of movement of the projection 21^a. 21^c indicates a stop fixed to and projecting laterally from the link 20 and arranged to be engaged by the tail 21^b of the pawl 21^b and prevent pivotal movement of the pawl when the projection 21^a engages therewith. With the pawl 21^b locked against movement in one direction it will be understood that upon the forward rotation of the pinion 19^c, the latter, through the connection 21 just described, will swing or revolve the link 20, which in turn will operate the gear sectors 18 through the rod 20^a and arm 20^b. When the pinion is rotated in the opposite direction the projection 21^a will engage with and ride the nose of the pawl 21^b by swinging the latter on its pivot. By imparting to the pinion angular movement slightly greater than one revolution thereof, it will always be returned to normal position with the projection 21^a in front of the pawl nose. 21^d indicates a spring, preferably of the coiled type and connected at one end to the link 20 in any well-known manner and connected at its opposite end to the pawl 21^b so as to normally maintain its tail against the stop 21^c.

19^b indicates a spring preferably coiled around the shaft on which the lever 17' is fulcrumed. One end of the spring is fixed in any well-known manner to the adjacent side member A, while its opposite end engages with the lever or rack and tends normally to maintain the free end of the lever upwardly in the position illustrated in Figs. 3 and 14. 22 indicates a pair of brackets secured to the adjacent side member A and preferably provided with flat springs 22^a which serve as buffers to cushion the rack and lever as they are moved in either direction about the fulcrum 19^a.

The platform B preferably comprises front and rear plates B', B^a, which are spaced from each other to form an opening b through which the storing rods D extend to receive type T. The rear plate B^a is provided with walls or surfaces 2 of varying heights, relative to the plate B', and the latter is provided with arms 3 which cooperate with a distributing device 22^a, which will be later described, to control the distribution of type therefrom, whereby the type to be stored after printing can be rapidly distributed to and upon the rods D.

The distributing device 22^a preferably comprises a casing, in which a series, preferably a complete line of type, is placed after removal from the drum of the printing machine, and from which the type may be successively discharged to or ringed upon the various rods D on which they are respectively stacked. The shape of the cas-

ing is preferably semi-cylindrical, but is slightly greater than a semi-circle to provide a shaft or support for a swingable pusher 23. The casing 22^x preferably has 5 a back or side wall 22^a, an end wall 22^b and a cover 22^c, hinged at 22^d to the wall 22^a. A spring 22^e may be provided and connected in a well known manner to the wall 22^a and cover 22^c normally to maintain the 10 latter closed. 22^f indicates a curved rib or wall mounted on the side wall 22^a and arranged concentrically to the axis on which the pusher 23 swings and forming with the end wall 22^b a channel 22^f to receive a line 15 of type T. 24 indicates an opening formed by cutting away the front end of the end wall 22^b. 24^a indicates a pair of abutments for holding the forwardmost type section T within the channel 22^f. The abutments 24^a 20 are connected to or formed integral with the opposite inner faces of the side wall 22^a and cover 22^c and are spaced from each other to receive between them the arm 3, over which the casing 22^x is placed each time 25 a type T is distributed to a rod D. The arm 3 is fixed to the plate B' and extends upwardly therefrom so as to engage the forwardmost type T in the channel 22^f. I provide an arm 3 for each rod D and arrange 30 it in front thereof. The abutments 24^a are preferably arranged to support the type T at a point above and relative to the lower edge of the casing 22^x, so that when the latter is placed over an arm 3 and upon 35 the platform B (see Fig. 4) and then drawn horizontally toward the operative, the arm 3 will engage with and arrest the forwardmost type T, and cause it to move through the opening 24 as the horizontal movement 40 of the casing 22^x takes place. Each arm 3 is preferably spaced relatively to the adjacent rod D so as to arrest it immediately above the rod with the opening in the type T in alignment with the rod D. As a result of this arrangement, as soon as the type 45 T is free of the casing 22^x, it will ring itself on the rod and slide downwardly thereon until it is stopped by the rod supporting and engaging members 16^a. If desired, the parts 50 may be so arranged that the upper free end of each rod D will extend partially through the forwardmost type T at the time the casing 22^x is positioned over the adjacent arm 3 onto the platform B.

55 The pusher 23 preferably consists of an arm 23^a loosely mounted on a shaft 23^{a'} carried by the back wall 22^a, a follower 23^b which extends laterally from the free end of the arm 23^a into the channel to engage the rearmost type T, and a spring 23^c which tends to swing the pusher 23^a about the shaft 23^{a'}, and maintain the forwardmost type T against the abutments 24^a. The spring 23^c is preferably coiled around the stud or shaft 23^{a'}. One end of the spring

may be fixed to the casing and its opposite end engages with the arm 23^a and normally tends to swing the pusher about the shaft towards the abutments 24^a, thereby serving to push or move the type through the channel 22^f and maintain the forwardmost one thereof in engagement with the abutments. 23^d indicates a stop preferably arranged to arrest the movement of the pusher at a point in line with the top of the opening 24. 75

The type T may be placed in the channel 22^f in any suitable manner, but preferably the type is retained on a segment bar 15 when the latter is disconnected from the printing drum. The segment 15 is transferred with the type T thereon to the channel 22^f, after which the cover 22^c may be closed and the segment bar 15 removed endwise through the type and from casing 22^x, the space between the abutments 24^a readily permitting this operation. 80

I preferably provide means for holding the pusher 23 at the rear end of the channel 22^f while a series of type T is being placed in the channel 22^f. These means 90 preferably comprise a flat spring 25 fixed to the outer face of the end wall and provided with an inturned end or catch 25^a adapted to extend through an opening in the end wall 22^b, engage with the follower 23^b and hold the latter at the rear end of the channel 22^f. When it is desired to fill the channel 22^f, the cover is thrown back and the pusher 23 moved into locking engagement with the spring catch 25^a; thereupon, the type T may be positioned in the channel, the cover 22^c closed and the pusher 23 released. 95

100 26 indicates a cam which may be carried by the cover 22^c. The object of the cam is to cause the automatic release of the pusher 23 upon the closing of the cover 22^c. For this purpose the cam 26 is positioned to engage the spring 25, as the cover 22^c is closed, elevate the spring and cause its inturned end to disengage the pusher 23. Upon being released, the pusher 23 will automatically swing about its shaft under the action of the spring 23^c into engagement with the rearmost type T. 110

115 It will be understood that the thickness of the type T depends upon the particular letter or character provided thereon. To prevent the discharge of more than one type through the opening 24, I preferably provide means for regulating or adjusting the size of such opening according to the thickness of each type to be discharged therethrough. These regulating means preferably comprise a gate 27 pivotally mounted upon the casing 22^x and the engaging walls or surfaces 2 carried by the plate B' with which the gate engages as the casing is positioned over each rod D in distributing a type section T thereto. The gate 27 preferably consists of an arm 27^b, the inner end 120

125

130

of which may be pivoted at 27^c upon the wall 22^a of the casing 22^x, a plate 27^d carried by the front end of the arm 27^a and adapted to open and close the opening 24 according to the distance that the arm 27^a is moved about its pivot, and a finger 27^e which extends forwardly for engagement with the walls 2. As will be readily understood, there is one finger engaging wall 2 adjacent each 10 rod D. The walls 2 are preferably formed on the upper surface of the plate B, or a plate b mounted thereon, rearward of the opening through which the rods D extend. The walls 2 are made of different heights relative 15 to the surface of the plate B', according to the thickness of the type to be stored on the rods, so that when the casing 22^x is positioned over the rods D, the finger 27^e will engage with the walls 2 and cause the plate 27^b to be opened to a greater or less extent, depending upon the height of each wall 2. Where the forwardmost type is relatively 20 thick, the wall 2 adjacent the rod D on which that particular type is to be stored, is relatively high, so that when the casing 22^x is positioned over the rod D onto the platform B, the gate 27 will be swung upwardly far enough to permit the discharge of the type; but where the forwardmost type to be 25 distributed is relatively thin, then the wall 2 adjacent the rod on which that particular type is to be stored, is relatively short, so that the gate 27 will be opened sufficiently to permit the discharge of that type section. 30 The gate is preferably maintained normally closed by a spring 28 which is preferably coiled around the shaft on which the gate is mounted, one end of the spring being attached to the gate 27 and its opposite end 35 fixed in a well known manner to the side wall of the casing 22^x.

As an index to the rods D and to facilitate the operation of distributing type, the platform B is provided with characters, as 40 shown at 4, one adjacent to each rod D, to designate the type to be distributed thereto. Likewise, to facilitate the setting of the type, I may provide a plate c' above the pockets 12^a and provide on such plate similar characters each adjacent to one of the rods D. The plate c' is preferably supported at its opposite ends by the upright members A, A.

In operation, assuming that there is certain type set up on a printing drum, and it is desired to distribute such type and thereafter reset it for printing purposes, each line of type T is mounted upon a segment such as illustrated at 15, in Fig. 12. This 50 segment with the type thereon is transferred from the printing drum and placed in the casing 22^x, the cover 22^e thereof being first opened and the pusher 23 swung to the rear end of the channel 22^f, the segment 15 can be 55 withdrawn endwise and the cover closed; this

latter operation serving to release the pusher 23, which thereupon swings about its axis into engagement with the type and maintains the forwardmost one against the abutments 24^a. The casing 22^x is then grasped by the operative and placed on the platform B and over the rod D (see Fig. 3), set apart for the type sections T, bearing characters like that on the forwardmost type. The positioning of the casing 22^x over the rod D causes the finger 27^e to engage the adjacent wall 2 and swing the gate upwardly sufficiently far to permit the discharge of the forwardmost type through the opening 24 (see Fig. 4). The operative then draws or slides the casing 22 towards him on the platform B, which operation effects the discharge of the forwardmost type T by its engagement with the arm 3. The operative then positions the casing over the rod D, which is to receive the next forwardmost type T, and causes the discharge thereof upon the rod D set apart for it. This operation is repeated until all of the type in the channel 22^f have been distributed. The casing 22^x is then re-filled with another line of type and such type are distributed, until all the lines of type have been distributed to the rods D. In distributing the type, the operative follows a copy of the matter which has been printed from the type. He is therefore readily able to tell what particular type T is positioned in the channel 22^f ready for discharge therefrom. From time to time, during the distribution of the type to the rods D, the operative swings the lever 17' downwardly, thus causing the rod engaging and supporting members 16^a, 16^b, to alternately release and engage the rods D and permitting the type which have been distributed to the rods D to slide downwardly thereon to the lower end thereof, the type stacking on top of each other, as shown in Fig. 1.

This operation may be effected each time a type section is distributed to one of the rods D, or the operative may wait until he has distributed several type sections or one or more complete lines of type. As the rod supporting and engaging members 16^a, 16^b, are moved laterally and caused to be disengaged from the rods D for a period of time, a plurality of type T can move by each pair of members while the latter is out of engagement with the adjacent rod D. Accordingly, the operative can take advantage of this fact and distribute several type T to each of the rods D, before it is necessary to operate the supporting and engaging members.

In setting the type, I preferably utilize the type segments 15, thereby making it unnecessary to set the type on a separate tool and then transfer it to a segment which holds each line of type on the printing drum.

The segment 15 is preferably pointed at one end and is inserted into and up through the openings 14 into engagement with the lowermost type of the stacks of type. The 5 operation of inserting the segment 15 into and up through one of the openings 14 is illustrated in Fig. 12. After the segment is inserted in this manner, the segment is moved forwardly, thus removing the lower- 10 most type from the pocket 12^a through the adjacent opening 13. As the operative will continue to press the free end of the segment 15 upwardly, the operative will automatically cause the segment to extend through 15 the opening in the type as it is moved through the opening 13, thus causing the type to ring itself on the segment. The segment 15 is then inserted into the opening below the stack of type bearing the next 20 letter which is to be set up in the line of type. The operative repeats this operation for each type according to the letters constituting the words in the line which is being set up until the complete line is set. 25 Thereupon, the segment 15 may be secured in the printing drum and additional lines set up in a similar manner.

In Fig. 14 I have illustrated a slightly modified form of the invention in which the 30 connections 21 between the gear sector 19^b and the link 20 are arranged to permit the pinion 19^c to move in anti-clockwise direction by the downward movement of the lever 17' without revolving the link 20, but to 35 revolve the link 20 when the pinion rotates in a clockwise direction under the action of the spring 19^a. In this form of the invention the position of the pawl is reversed so as to lock the link thereto by the engagement of the projection 21^a, when revolving 40 about its axis in a left-hand direction, but to permit the movement of the projection past the nose of the pawl when the pinion revolves in the opposite direction. When 45 the connections 21 are arranged for operation in this manner, the spring 19^b is strong enough to return the lever 17' to normal position and through the gear sector 19^b thereon to operate the link 20, connecting 50 member 19 and gear sectors 18, as hereinbefore described. When the connections are arranged in this manner I preferably provide a regulating device, such as a cylinder having a piston connected to the lever 17' 55 and an air valve, whereby the return of the lever will be regulated. The purpose of this construction is to provide for the uniform operation of the rod supporting and engaging members 16^a, 16^b, so as to permit the 60 dropping of the type sections downwardly into stacked position. By causing the gear sector 19^b to operate in one direction under the action of a spring and a regulating device the operating means will actuate the 65 members 16^a, 16^b, in a uniform manner and

with the same force. When the operating devices are constructed and arranged for operation in this manner, the operative may readily and quickly swing the lever 17' downwardly, thus putting under tension the 70 spring 19^b which will then return the sector 19^b to normal position and in so doing operate the rod supporting and engaging members 16^a, 16^b.

This application is a division of my application filed January 6, 1917, Serial Number 140,989.

To those skilled in the art of making apparatus of the class described, many alterations in construction and widely differing 80 embodiments and applications of my invention will suggest themselves without departing from the spirit and scope thereof. My disclosures and the description herein are purely illustrative and are not intended to 85 be in any sense limiting.

What I claim is:

1. In apparatus of the character described, the combination of a member adapted to hold type in stacked relationship, and means 90 for supporting said type holding member, said means being controlled and actuated while supporting said member to permit movement of the type endwise thereof.

2. In apparatus of the character described, the combination of a support on which the lowermost type of a stack rests, an upright member to which type is distributed, said member serving to hold said type in stacked relationship, and means for supporting said holding member intermediate its ends, said means being disengageable from said member to permit movement of the type endwise thereof.

3. In apparatus of the character described, the combination of a support on which the lowermost type of a stack rests, an upright member to which type is distributed, said member serving to hold said type in stacked relationship, and means for supporting said member intermediate its ends with its lower free end spaced from said support, whereby the lowermost type may be removed.

4. In apparatus of the character described, the combination of a support on which the lowermost type of a stack rests, an upright member to which type is distributed, said member serving to hold said type in stacked relationship, and means for supporting said member intermediate its ends with its lower free end spaced from said support, whereby the lowermost type may be removed, said supporting means being constructed and arranged to permit movement of the type endwise of said member.

5. In apparatus for holding apertured type, the combination of a support on which the lowermost type of a stack of type rests, and means extending through the apertures in the type for holding it in stacked relation-

ship on said support, said support being formed with a recess which permits the insertion of a tool upwardly into engagement with the lowermost type and the removal thereof laterally from said support.

6. In apparatus for holding apertured type, the combination of a support provided with a pocket in which the lowermost type of a stack of type rests, the front wall of said pocket being formed with an opening to permit the successive discharge of the type in the stack, and means extending through the apertures in the type for supporting it in stacked relationship in said pocket, the wall of said support being formed with a recess through which a tool is inserted into engagement with the lowermost type to cause its removal through the opening in the front wall of said pocket.

7. In apparatus for holding apertured type, the combination of a support, a member adapted to extend through the apertures in the type and hold it in stacked relationship and means carried by said support for supporting said member thereon in a manner which permits the distribution of the type to one end of the member and the discharge or removal thereof from the opposite end of the member, said supporting means permitting movement of the type endwise of said member.

8. In apparatus of the class described, the combination of a support, a member adapted to receive and hold a plurality of type in stacked relationship, means carried by said support and engaging said member between its opposite ends for supporting it thereon in a manner which permits the distribution of the type to one end of the member and the discharge or removal thereof from the opposite end of the member, and means for controlling and actuating said supporting means to support said member while permitting the type to move endwise of said member.

9. In apparatus of the class described, the combination of a support, a member adapted to receive and hold a plurality of type in stacked relationship, means carried by said support for supporting said member thereon in a manner which permits the distribution of the type to one end of the member, said means comprising devices engaging said rod in different planes intermediate its ends, and means for controlling and actuating said devices alternately to disengage them from said members and permit movement of the type endwise of said member.

10. In apparatus of the class described, the combination of a support, a member adapted to receive at its upper end a plurality of type, means carried by said support for supporting said member in upright position in a manner which permits the dis-

tribution of type to its upper end and the discharge or removal thereof from the opposite end of said member, said means comprising devices engaging said rod in different horizontal planes intermediate its ends, and means for controlling and actuating said devices alternately to disengage them from said member and permit movement of the type endwise of said member.

11. In apparatus of the class described, the combination of a support, a member adapted to hold a plurality of type in stacked relationship, upper and lower pairs of movable members engaging said rod intermediate its ends for supporting said rod in upright position, and means for operating said pairs of supporting members alternately to disengage them from said member and permit type distributed to said holding member to move endwise thereof.

12. In apparatus of the class described, the combination of a support, a member adapted to receive and hold a plurality of type in stacked relationship, upper and lower pairs of devices normally engaging said member for supporting it with its free end spaced from said support, and means for alternately moving said pairs of supporting devices away from said type holding member to permit type distributed thereto to move endwise of said member.

13. In apparatus of the class described, the combination of a support, an upright member adapted to receive and hold type in stacked relationship, upper and lower pairs of devices for engaging and supporting said member intermediate its ends, means normally tending to hold said devices in engagement with said member, and means for operating said pairs of devices alternately to permit type distributed to said member to move endwise thereof.

14. In apparatus of the class described, the combination of a support, a member adapted to receive type at one end and support them in stacked relationship, pairs of devices engaging said member in different planes intermediate its ends for supporting it on said support, and means for moving said pairs of devices alternately away from said member to permit movement of the type thereon endwise, said means maintaining one pair of devices in engagement with said member while the other pair of devices is moving away from and toward said member.

15. In apparatus of the class described, the combination of a support, a member adapted to receive type at one end and support them in stacked relationship, pairs of devices engaging said member in different planes intermediate its ends for supporting it on said support, and means for moving said pairs of devices alternately away from said member to permit movement of the

type thereon endwise, said operating means comprising rockers having operative engagement with said pairs of devices and movable in opposite directions simultaneously.

16. In apparatus for holding perforated type, the combination of a support including a series of members each adapted to extend through the perforations in the type and hold them in stacked arrangement, means for supporting said members, and means controlling said supporting means and permitting the type distributed thereto to slide endwise of the members.

17. In apparatus of the character described, the combination of a support including a series of members adapted to receive and hold type in stacked arrangement, means removably engaging said members between their opposite ends for supporting them with their lower free ends spaced from said support, and means controlling said supporting means and permitting the type distributed thereto to slide endwise of the members.

18. In apparatus of the class described, the combination of a support, a series of upright members each adapted to receive type and hold the same in stacked relationship, means comprising an upper series of pairs of devices and a lower series of pairs of devices for engaging and supporting said upright members intermediate their ends, and means for alternately operating said series of upper and lower pairs of devices.

19. In apparatus of the class described, the combination of a support, a series of upright members each adapted to receive type and hold the same in stacked relationship, means comprising an upper series of pairs of devices and a lower series of pairs of devices for engaging and supporting said upright members intermediate their ends, and means for operating said upper series of pairs of devices and thereafter operating said lower series of pairs of devices, whereby one series of pairs of devices is maintained in engagement with said upright members while the other series of pairs of devices are being operated.

20. In apparatus of the class described, the combination of a support, an upright member adapted to receive and hold a plurality of type in stacked relationship, pairs of upper and lower devices normally adapted to engage and support said member intermediate its ends, a device interposed between one supporting device of one pair and the adjacent supporting device of the other pair of supporting devices for moving said supporting devices alternately away from said member, and means for swinging said operating devices simultaneously in opposite directions.

21. In combination in a distributing de-

vice for type, a frame provided with a platform having an opening, rods retained in a vertical position in said frame underneath said opening, supporting means in said frame for said rods, arranged at different levels, and means for alternately engaging and disengaging said supporting means with said rods.

22. The combination with a frame, of a series of type holding rods, means, arranged in different horizontal planes, for supporting said rods in upright position, and devices for alternately moving said supporting means away from and toward said rods.

23. In an apparatus for holding type, a frame, a series of rods, series of vertically spaced upper and lower devices for supporting said rods, and means for alternately withdrawing the upper and lower supporting devices and re-engaging them with said rods to permit the type to fall from one level to another and pass said supporting devices.

24. In an apparatus for holding type, a frame, a series of rods, series of vertically spaced upper and lower devices for supporting said rods, means for alternately withdrawing the upper and lower supporting devices and re-engaging them with said rods to permit the type to fall from one level to another and pass said supporting devices, and a member to arrest the downward movement of said type.

25. In a device for holding perforated type, a frame, a series of rods, series of upper and lower devices for supporting said rods, means for alternately withdrawing the upper and lower supporting devices and re-engaging them with said rods to permit the type to pass said supporting devices, and a member upon which said type fall, said receiving member being provided with a lateral opening through which said type can be withdrawn one at a time.

26. In apparatus of the class described, the combination of a frame, a series of vertically disposed type holding rods therein, retaining devices in the frame for said rods, said retaining devices arranged at different levels, means for operating said retaining devices to disengage the same from said rods at one level while simultaneously engaging the same therewith at the other level, a device upon which the type rest spaced from the foot of each rod.

27. In a storing device for type, the combination of a frame, a series of rods, pairs of upper and lower devices having their inner ends adapted to engage and support said rods, and means for operating said respective pairs of devices alternately, whereby one pair will engage with and support said rod at the time that the other pair is released from the same, to permit the passage of the type along said rod.

28. In a storing device for type, the com-

bination of a series of rods upon which said type are stored, a base member upon which said type fall by gravity, said member being spaced from the lower ends of said rods 5 to permit the removal of the lowermost type from each rod, and enclosing means for the lowermost type on each rod, each enclosing means being provided with an opening at one side and said base member being provided with openings extending underneath 10 the type for the introduction of a tool for removing the same.

29. In apparatus of the class described, the combination of a support on which a 15 plurality of perforated type may be stacked with their perforations in alignment, a rod extending through the perforations of the type to hold them in stacked relationship and permitting the type to move endwise 20 thereof, the rod being entirely surrounded by the type, and means for supporting said rod with its free end spaced from said support while permitting the type to be moved from end to end thereof, such supporting 25 means having intermittent engagement with the rod to permit the type to slide past them toward the free end thereof.

30. In apparatus of the class described, the combination of a support on which a 30 plurality of perforated type may be stacked with their perforations in alignment, side walls mounted on said support to form a pocket for the lowermost types in the stack of type, one of said side walls being formed 35 with an opening through which the lowermost type may be removed, a rod extending through the perforations of the type and serving to maintain them in stacked relationship the rod being entirely surrounded 40 by the type, and means for supporting said rod with its free end spaced from said support while permitting the type to be moved from end to end thereof, such supporting means having intermittent engagement with the rod to permit the type to slide past them 45 toward the free end thereof.

31. In apparatus of the class described, the combination of a support on which a 50 plurality of perforated type may be supported in stacked relationship, a rod extending through the perforations in the type for maintaining them in stacked relationship the type entirely encircling the rod, and means for supporting said rod with its lower 55 free end terminating at a point substantially midway between the upper and lower surfaces of the type adjacent to the lowermost type of the stack, whereby the lowermost type may be removed without removing 60 the type thereabove, the supporting means for the rod having intermittent engagement therewith to permit the encircling type to slide past such supporting means while out of engagement with the rod.

32. In apparatus of the class described,

the combination of a support on which a plurality of perforated type sections may be supported in stacked relationship, walls mounted on said support and forming a 70 pocket for the lowermost sections of the type in the stack, the front wall of said pocket being formed with an opening through which the type sections are successively removed, a rod extending through the perforations in the type sections for maintaining them in stacked relationship the type entirely encircling the rod, and means for 75 supporting said rod with its free end terminating at a point substantially midway between the upper and lower surfaces of the 80 type section adjacent to the lowermost type section and co-operating with the front wall of the pocket to prevent the removal of the type sections above the lowermost type, the supporting means for the rod having intermittent engagement therewith to permit the 85 encircling type to slide past such supporting means while out of engagement with the rod.

33. In apparatus of the class described, 90 the combination of a support on which a plurality of perforated type are adapted to be supported in stacked relationship, said support being provided with a slot extending inwardly from its front edge to permit the introduction of a tool thereinto to engage the perforation in the lowermost type of the stack, a rod extending through the perforations in the type for maintaining them in stacked relationship, and means for supporting said rod with its free end spaced from said support, whereby the lowermost type can be removed.

34. In apparatus of the class described, 95 the combination of a support on which a plurality of perforated type are adapted to be supported in stacked relationship, a rod extending through the perforations of the type and serving to maintain them in stacked relationship the type entirely encircling the rod, disengageable means for supporting said rod intermediate its ends with its free end spaced from said support while permitting the movement of the type from end to end of said rod, and a wall arranged in front of said support and adapted to be engaged by one or more type above the lowermost type to prevent the removal of type thereabove.

35. In apparatus of the class described, 100 the combination of a support on which a plurality of perforated type are adapted to be supported in stacked relationship, front, rear and side walls mounted on said support and arranged to form a pocket for the lowermost type in the stack, a rod extending through the perforations of the type for maintaining them in stacked relationship the type entirely encircling the rod, and 105 disengageable means supporting said rod in- 110

termidate its ends above the type stacked thereon with the lower free end of said rod spaced from said support, but permitting the movement of the type from end to end 5 of said rod, the walls of said pocket operating through the type to prevent lateral movement of the lower free end of said rod.

36. In apparatus of the class described, the combination of a series of upright rods, 10 means for supporting said rods with their upper ends exposed, a platform common to and extending in front of said rods, and devices mounted on said platform, one for each rod, adapted to engage perforated type in a 15 holder to cause the ringing thereof on the free ends of said rods.

37. In apparatus of the class described, the combination of a series of vertical rods, 20 one for each character of a font of type, pairs of devices arranged to engage said rods between their opposite ends for supporting them in upright position, a pair of rock-shafts having members arranged to engage said pairs of devices and alternately move 25 them toward and from said rods, gearing connecting said rock-shafts together, whereby they may be simultaneously rocked in opposite directions, and means for operating said gearing.

38. In apparatus of the class described, the combination of a series of vertical rods, one for each character of a font of type, pairs of devices arranged to engage said rods between their opposite ends for 30 supporting them in upright position, a pair of rock-shafts having members arranged to engage said pairs of devices and alternately

move them toward and from said rods, gearing connecting said rock-shafts together, whereby they may be simultaneously rocked 40 in opposite directions, means for operating said gearing, and means for controlling the movement of said operating means.

39. In apparatus of the class described, the combination of a series of rods around 45 which type are stacked, upper and lower sets of devices removably engaging said rods to support them but permit movement of the type from end to end thereof, means for alternately operating said sets of devices, 50 and means for controlling said operating means.

40. In apparatus of the class described, the combination of a series of rods around 55 which type are stacked, upper and lower sets of devices removably engaging said rods to support them but permit movement of the type from end to end thereof, means, including a spring which is placed under tension, for alternately operating said sets of 60 devices, and means for controlling the operation of said operating means under the action of said spring.

41. In apparatus of the class described, the combination of a support, a rod on 65 which articles may be ringed, means engaging said rod for supporting it on said support, and mechanism for controlling said engaging means, whereby the articles may be moved from end to end of said rod while 70 supported on said support.

In testimony whereof, I have hereunto signed my name.

ARTHUR D. SABORSKY.
